VEHICLE WINDOW REGULATOR
MECHANISM

John B. Parsons, Toledo, Ohio

Application August 8, 1945, Serial No. 609,599

2 Claims. (Cl. 268—126)

1

This invention relates to a window regulator mechanism particularly adapted for controlling a vehicle window between the open and closed positions.

An object of this invention is the production of a new and improved window regulator having the free ends of a plurality of straight members slidably connected to the window edge and the other ends and intermediate sections interconnected in a manner to impart the desired window movement upon actuation.

Another object of this invention is to provide a new and improved window regulator of the above type comprising simply formed elements which impart the desired window movement upon actuation of the assembled parts.

A further object of this invention is to provide a regulator mechanism adapted to the rear quarter sedan window which acts through lever members to impart the desired window movement upon manual, mechanical or hydraulic actuation.

Other objects and advantages of the invention will hereinafter appear, and for purposes of illustration but not of limitation, embodiments of the invention are shown in the accompanying drawings in which

Figure 1 is a side elevational view of the regulator mechanism showing the hydraulic system for actuation and the rear quarter window in a substantially lowered position;

Figure 2 is a cross sectional view substantially on the line 2—2 of Figure 1; and

Figure 3 is a top view of the regulator mechanism shown in Figure 1.

The illustrated embodiment of the form of invention shown on Figures 1 to 3 comprises a rear quarter vehicle window 10 guided for horizontal movement and vertical movement by a channel 11 and supported by a cushioned channel member 12 with two attached downwardly depending L-shaped tongues 13. The attachment of retainer members or guides 14 to the tongues 13 by means of bolts 15 movable in slots 16, permits the vertical adjustment and attachment of the window panel 10 in relation to the retainer members 14. Studs 17 are attached to the ends of a straight regulator arm member 19 and another substantially equal length parallel arm member 18 which is offset near its lower end portion as shown in Figure 3, said studs being adapted for sliding movement in the horizontally elongate slots 20 in the retainer members 14. One end of a cross link 21 is pivotally connected to the near end portion of the arm member 18, the other end of said cross link being pivotally con-

2

nected to the central portion of the arm member 19. Another cross link 22 offset as shown in Figure 3 to avoid other elements of the mechanism, is pivotally attached to the central portion just below the offset of the arm member 18, the other end being pivotally attached to the lower end of the arm member 19 where also the upper end of the frame arm 23 is connected for rotational movement. The lower end of the frame arm 23 is pivotally connected to one end of a stationary horizontally disposed cross arm 24 which is also connected at the other end to a vertically disposed stationary frame arm 25 held by a bracket 26 to the automobile body frame. The upward movement of a rotatable lever arm 27 which is attached to the lower end of the frame arm 25, is restricted by a stop 28 secured to the lower end portion of the frame arm 23. A clamp 29 on the lever arm 27 retains a ball and socket joint 29a which connects to the lower end portion of a hydraulic cylinder and piston assembly 30. Another clamp 31 on the lower portion of the arm member 18 holds a ball and socket joint 31a which attaches to the upper end of the piston rod 32. The ball and socket joints 31a and 29a permit rotational as well as bending movement of the hydraulic assembly 30 in relation to the enclosing frame arms 23 and 25. Further description of the hydraulic system and its operation is deemed unnecessary in view of its common usage by those skilled in the art. Suffice it to say that on the entrance of fluid pressure through a port 30b will cause the piston and piston rod 32 to rise, whereas release of fluid from the cylinder will enable a corresponding downward movement of the piston and rod. A helical coil spring 33 is disposed alongside of the hydraulic assembly, one end of said spring being anchored to the lever arm 27 and the upper end attaching to the center of the cross link 22.

It will be manifest that entrance of pressure fluid into the cylinder 30a through the hose connection 30b causes the piston and piston rod 32 to move upwardly, imparting an upward movement to the arm member 18 which by interaction through the cross links 21 and 22, causes a similar movement of the straight arm member 19. The upward movement of the arm members 18 and 19 results in a swinging movement of their ends which coat with the slotted retainer members 14 to raise the vehicle window panel 10. When fluid is released from the cylinder 30a, the static forces in the helical coil spring 33 cause

the movement of the elements in the reverse direction.

The relatively longitudinal disposition of the parallel arm members 18 and 19 permits the location of the operating elements to be situated off to one side of the window panel. This desirable characteristic relates to the limited space available in the rear quarter body structure.

It is apparent that I have devised a means by which the rear quarter window of a vehicle may be regulated through the interaction of simple straight arm members which can be made from ordinary sheet metal stampings. The simplicity of construction affords the advantages of prior assembly which is suitable to modern mass production methods, and the means of operation permits the use of manual, hydraulic or mechanical actuation.

It is to be understood that numerous changes in details of construction, arrangement and operation may be effected without departing from the spirit of the invention especially as defined in the appended claims.

What I claim is:

1. A window regulator mechanism comprising two relatively straight arm members operatively connected to the lower edge of the window panel, a link, a pivotal connection between one end of said link and the upper portion of one of the relatively straight arm members, a pivotal connection between the other end of said link and the central portion of the other arm member, a second link, a pivotal connection between one end of said second link and the lower portion of the first relatively straight arm member, a pivotal

connection between the other end of said second link and the lower end of the other arm member, a relatively fixed support, a pivotal connection between the lower end of said first relatively straight arm member and the upper end of said fixed support, a pivotal connection between the lower end of the other arm member and the fixed support, and means for imparting swinging movement to said relatively straight arm members.

2. A regulator mechanism as claimed in claim 1, in which the actuating means comprises a hydraulic piston and cylinder assembly connected to one of said relatively straight arm members for upward actuation, and a helical coil spring attached to one of said links for actuating movement in the lowered direction.

JOHN B. PARSONS.
